UNITED STATES PATENT OFFICE.

GEORGE J. RATHBUN, OF TOLEDO, OHIO, ASSIGNOR TO INGERSOLL-RAND COMPANY, OF JERSEY CITY, NEW JERSEY, A CORPORATION OF NEW JERSEY, JOINTLY WITH THE RATHBUN-JONES ENGINEERING COMPANY, A CORPORATION OF OHIO.

OIL PUMP FOR COMBUSTION ENGINES.

Application filed April 25, 1924. Serial No. 708,837.

To all whom it may concern:

Be it known that I, GEORGE J. RATHBUN, a citizen of the United States, and a resident of Toledo, county of Lucas, and State of 5 Ohio, have invented a certain Oil Pump for Combustion Engines, of which the following is a specification, accompanied by drawings.

This invention relates to oil engines but more particularly to pumps for injecting oil 10 unmixed with air into the cylinders of such engines commonly known as solid injection pumps.

In multi-cylinder oil engines, it has been found expedient to inject the fuel into combustion chambers of the cylinders by means 15 of a single pump and a device for distributing the fuel at the proper times to the various cylinders. In order to provide the proper number of fuel injections into the 20 cylinders, the pump is operated at a rate higher than the crank shaft speed, the pump speed depending upon the number of cylinders. The pump speed in the case of engines having six or more cylinders becomes 25 comparatively high as, for instance, in the case of a six-cylinder motor operating on the four-stroke cycle at 500 R. P. M., the pump plunger will reciprocate at the rate of 1500 times per minute in order to provide the 30 necessary six injections during each two revolutions of the crank shaft. This high pump speed introduces a difficulty in operating any pump construction which is not present at lower speeds. The use of cams 35 for guiding the pump plunger at a high speed has been found to be not entirely satisfactory as the parts used to operate the pump plunger must be made heavy and cumbersome and the wear on the cam is excessive. A means more preferable than 40 cams for this use is an eccentric and a direct connected push rod. This permits the use of a cross head associated with the pump plunger to actuate and guide the pump 45 plunger. The use of an eccentric introduces a difficulty in that the pump plunger is continuously moving in a simple, harmonic motion and, consequently, the pumping stroke is of too long duration. An additional difficulty 50 is introduced by the fuel distributor for the reason that there are periods when the oil passage is completely blocked and at such times a high pressure on the pump

would be apt to ruin parts of the distributor. This difficulty is not present when a 55 cam of the proper shape is used but, with the exception of certain special cases, certain parts of the pump stroke must be rendered ineffective when this plunger is operated by an eccentric.

It is, accordingly, the object of the invention to enable the pump plunger to be operated by an eccentric and to render ineffective certain portions of the pumping stroke to obviate the difficulties above referred to. 60

Further objects of the invention will be in part obvious and in part pointed out hereinafter.

In the drawings forming part of this specification and in which similar reference 70 characters refer to similar parts,

Figure 1 is a side elevation of a multi-cylinder engine, embodying the features of this invention,

Figure 2 is a vertical section of the fuel 75 injection pump and the end portion of the engine base showing the driving connections for the pump,

Figure 3 is a vertical section through the pump cylinder and the passages leading to 80 and from the pump for conveying the fuel oil, and

Figure 4 is a side elevation of the engine, parts being broken away to show the governor controlling the by-pass valve associated 85 with the pump, and the driving connections therefor.

Referring to the drawings, there is illustrated an engine having a base A upon which are mounted a plurality of cylinders 90 B, as for instance six, each operating on the principle disclosed in U. S. Patent No. 1,517,015 of November 25, 1924, granted to William T. Price, each of the cylinders B being provided with a head C within 95 which are housed suitable valves operated by the push rods D. Preferably the cylinders B are water jacketed, being connected by a suitable pipe E with a water pump F driven through suitable gearing by the drive shaft 100 G of the engine.

The fuel, which may be of any suitable liquid, such as fuel oil, is fed selectively to the cylinders B through the medium of a distributor H of the type described in co-pending application Ser. No. 708,835 filed 105

April 25, 1924, having tubes J leading to the injection nozzles K. Fuel is supplied to the distributor H from a pump shown in detail in Figures 2 and 3, which is mounted 5 on the forward end of the base A in the manner hereinafter described.

The fuel pump includes a frame L upon which is supported in any suitable manner, as by the stud bolts O, the block P within 10 which there is a chamber Q having an inlet R through a valve seat S, held in the block P by means of a screw threaded bushing T. An outlet for the fuel oil is provided in the passage U leading from the chamber Q 15 through a suitable check valve V to a tube W connecting the pump to the distributor H. There is also provided a by-pass X associated with the outlet W, through which fuel in excess of the quantity required is led 20 back to the fuel supply source. The opening to the by-pass X is controlled through the medium of a by-pass valve Y preferably constructed to operate in the manner described in copending application of William T. 25 Price and George J. Rathbun, Ser. No. 399,993, filed July 29, 1920. The by-pass valve provides a means to vary the duration of the fuel injection period. The pump is provided with a plunger Z reciprocating in an 30 accurately bored guide a extending through the frame L and having a flange b by which the guide is rigidly held between the frame L and the block P. At the inlet R there is 35 provided a check valve c which is drawn open upon the downward stroke of the plunger Z and is closed on the upward stroke thereof. Suitable fittings are provided by the nipple d and the pipe connection e for a pipe leading from a reservoir of any 40 desired construction to conduct the fuel oil to the pump chamber Q.

The plunger Z is reciprocated by an eccentric f mounted on a shaft g which is rotated by means of a suitable gearing system 45 such as the gear h and the pinion j. The ratio of the gear h and the pinion j is such as to produce a reciprocation of the plunger for every fuel injection desired, thus, assuming that the engine illustrated comprises 50 six cylinders operating at a four-stroke cycle, the ratio of the gearing to the pinion j will be three to one which means that there will be three pumping strokes of the plunger Z to each revolution of the 55 crank shaft G. The eccentric shaft g may also be employed to drive the centrifugal water pump F associated with the cooling system. The bearing k for the shaft g is 60 provided with a web o formed integrally with the end housing p of the engine base. An oil seal for the shaft g is provided at the point at which the shaft g extends through the housing. Preferably the seal is 65 provided by flanges q cooperating with pockets r formed integrally with the hous-

ing p. Additional bearings s are provided at either side of the eccentric f and are supported by extensions t of the housing p.

The eccentric f is provided with a connecting rod u coupled by means of a wrist 70 pin v to a tappet w in the form of a piston which is adapted to slide in a cylindrical guide x formed in the housing p. The wrist pin v is held in place in the tappet by means of suitable bolts y. In the upper face of the 75 tappet w there is provided a small block z set into the tappet and adapted to bear against the adjusting member 2 fitted on the end of the plunger Z and adjustable with respect thereto by means of a nut 3 and co-operating threads 4 on the end of the plunger. The adjusting member 2 may be adjusted with respect to the plunger Z by turning the nut 3 thereby causing the adjusting member to be moved longitudinally in the 80 desired direction on the end of the plunger Z. The eccentric f through the medium of the tappet w and its associated parts, as above described, forces the plunger Z upwardly. The down stroke of the plunger Z 85 is caused by a coil spring 5 bearing on its upper end against the lower face of the top of the frame L and its lower end pressing against the cup washer 6 supported on the plunger Z by means of a flange 7 upset 90 thereon.

In operating an engine of this type it is usual for the injection to take place during only a fraction of the cycle. For instance, it may be desired to limit the injection of fuel 100 into the cylinders to say 20° of one revolution of the crank shaft. It is evident that with a pump constructed as above described, the plunger Z is operating continuously and that during one of its strokes it is continuously pumping, the other or return stroke being a suction stroke. Since in this particular case the pump shaft g is rotating three times as fast as the crank shaft G, each 105 pumping operation of the plunger Z occupies one sixth of a revolution of the crank shaft, that is to say, 60°. Such a long injection is ordinarily not desired and therefore a portion of the pumping stroke of the plunger Z may well be eliminated. Heretofore this has been done by actuating the pump plunger by means of a non-circular cam. However, due to inherent advantages of employing a circular cam or eccentric for 110 operating the plunger, additional means are employed to nullify the effect of the undesirable portion of the pumping stroke. The by-pass valve Y is not equipped to take care of the large volume of oil that would be 115 pumped therethrough if this were the sole means employed for this purpose and preferably the means for this end are independent thereof. In accordance with the invention, means are provided to hold the inlet valve c open during the interval in the time 120 125 130

of the stroke in which it is desired to pump no fuel through the outlet *W*. This means includes a pair of hooks 10 and 11 adapted to engage with each other, the former being attached to the upper face of the plunger *Z* and the latter to the inlet valve *c*. About these hooks and held in place thereby, there is provided a coil spring 12, one end of which bears against the face of the plunger *Z* and the other against the inlet valve *c* pressing in the part, as it were, and tending to press the valve *c* to its seat to close the inlet. Thus as the plunger *Z* descends on its suction stroke, its hook 10 will engage the hook 11 on the inlet valve *c* to unseat the valve and reduce the resistance to inflowing fuel. At the time when the plunger *Z* is at the lower limit of its stroke, the inlet valve *c* is being held open and remains so until the plunger *Z* reaches the predetermined point at its upward stroke whereupon the hooks 10 and 11 mutually disengage, and the injection of fuel from the chamber *Q* through the passage *U* of the pipe *W* to the injection nozzles *K* continues until the by-pass valve *Y* is operated to again relieve the pressure and discontinue the flow of fuel through the supply pipe *W*. The time at which the hooks 10 and 11 disengage may be adjusted by means of the adjusting member 2 controlled by the adjusting nut 3; that is to say, if it is desired to shorten the duration of fuel injection, the plunger *Z* may be lowered to the desired degree by means of the adjusting nut 3 so as to produce the effect of keeping the hooks 10 and 11 in engagement for a greater portion of the timing stroke. On the other hand, if it is desired to lengthen the duration of fuel injection, the plunger *Z* may be raised by screwing the nut 3 in the opposite direction to shorten the portion of the pumping stroke during which the hooks 10 and 11 are in engagement.

The speed or power delivered by the engine is regulated by the by-pass valve *Y* which controls the duration of fuel injection either automatically or manually, as desired. The by-pass valve *Y* cooperates with a seat 13 and when depressed is adapted to permit the passage of fuel from the pump chamber *Q* through the check valve *V* into passages 14 and thence to the by-pass *X*, leading to the reservoir or other suitable source of supply for the pump. The seat 13 and the passages 14 are formed in a guide 15, held in place in the pump body *P* by means of a nipple or bushing 16. The by-pass valve *Y* is provided with a shank 17 which extends beyond the guide 15 so that it may be actuated at the proper intervals and timing to perform its functions. The mechanism here shown for operating the by-pass valve *Y* includes an eccentric 19 on the shaft *g* for operating a pitman or connecting rod 20 having a sleeve bearing 21 on the eccentric 19, a plunger 22 connected to the pitman 20 by means of a wrist pin 23 and adjustable extension member 24 attached to the plunger 22, a lever 25 pivotally mounted at the end of the member 24 and having a contact screw 26 adapted to bear against the shank 17 of the by-pass valve *Y*, and a movable fulcrum member 28 adapted to bear at any desired point along the curved surface 29 on the lever 25. As the shaft *g* rotates, the lever 25 is continuously oscillating back and forth about the tip of the fulcrum 28 as the center. This rate of oscillation is the same as the rate of reciprocation of the plunger *Z* and at a definite predetermined relation thereto. The timing of the opening of the by-pass valve *Y* is determined by the extent of the motion of that end of the lever 25 at which the screw 26 is located. A slight amount of play is left between the point of the screw 26 and the upper face of the shank 17 so that with the fulcrum 28 in its extreme position at the left as shown in Figure 2, there is no opening of the by-pass valve *Y* as the lever 25 oscillates. However, when the fulcrum 28 is moved over toward the right, the by-pass valve is depressed sooner as the lever arm to the left of the fulcrum increases. This causes at the valve *Y* a quicker and greater opening to release the pressure in the supply pipe *W* in proportion as the fulcrum 28 is moved toward the right. This earlier release of pressure results in reducing the amount of fuel supplied to the injection nozzles *K* by decreasing the relative injection period, and a corresponding reduction of power developed by the engine.

The operation of the fulcrum 28 may be either automatic or manual. If it is desired to maintain a constant speed in the engine regardless of the power delivered, the fulcrum 28 may preferably be controlled by an automatic governor such as, for instance, of the centrifugal type. Such an arrangement is illustrated in Figure 2 wherein it will be seen that the fulcrum 28 is pivoted on a shaft 31, the center of which is at the center of the curved surface 29 of the lever 25. The shaft 31 is suitably journaled in a frame 32 and has an arm 33 which is attached to a vertical rod 34 extending downwardly and attached to a rotating cage 35. A pair of centrifugal governor balls 36 pivotally mounted on a spider 37 are provided at the ends with arms 38 cooperating with links 39 to depress the cage 35 when the balls are extended by centrifugal force. The spider 37 is rotated by a pair of beveled gears 40 and 41, the latter being mounted on a shaft 42 with a gear 43 meshing with the gear *h* in Figure 4. The gear 43 is shown forwardly of the pinion *j*, the latter not being seen in Figure 4 because of its rearward position. The shaft 42 is supported partly by a bearing 44.

ing 44 in the web σ . It will be noted that as the speed of the drive shaft G increases, the balls 36 move outwardly being partly restrained by the action of a spring (not shown), and causes the lowering of the cage 35. A corresponding lowering of the rod 34 occurs, and through the medium of the small arm 33 the fulcrum 28 is moved to the right, Figure 2, causing earlier opening of the bypass valve Y in the pumping stroke of the plunger Z . The supply of fuel to the injection nozzles K is thereupon reduced and the power of the engine decreases accordingly to result in a tendency to slow up the drive shaft G .

Occasionally an adjustment may be desirable in the lever 25 due to wear or other causes, and to this end the member 24 is made adjustable longitudinally with respect to the plunger 22. A pair of diagonally disposed set screws 46 are provided extending through the plunger 22 to contact with angular notches 47 in the member 24. The set screws 46 are located at an angle to each other, so that upon loosening one and tightening the other the member 24 may be shifted thereby longitudinally with respect to the plunger 22.

A slight amount of leakage of the fuel oil is usually present in pumps of this character. That which leaks through the joint between the guide member a and the pump body P may find its way to the bore in the frame L in which the plunger 22 slides. This oil provides sufficient lubrication to the bearing surface of the plunger 22 and to

the wrist pin 23, there being provided a bore 48 connected to the exterior of the plunger 22 by a passage 49.

The oil which leaks from the pump chamber Q out through the slight space between the guide a and the plunger Z may find its way through a passageway 51 and a drip 52 into a groove 53 from which the oil may be collected and reused.

The base A of the engine may be provided with plates 55 and 56 which are movable to permit access to the bearings of the connecting rods and drive shaft of the engine. Additional access is also provided by hand-holes having removable covers 57 on the lower part of the base, as well as the hole covered by the plate 58.

I claim:

A pump for a combustion engine comprising the combination of a frame, a shaft having an eccentric, a tappet, a connecting rod connecting said tappet and said eccentric, a block provided with a chamber and mounted on said frame, a spring pressed plunger in said chamber arranged to be actuated by said tappet, a guide support between said frame and block for said plunger, an inlet, and inlet valve in said chamber inlet, and mutually engaging members on said plunger and said inlet valve to hold said valve open for a portion of the pumping stroke of said plunger, an outlet and a bypass for said chamber.

In testimony whereof I have signed this 7th specification.

GEORGE J. RATHBUN.
